CLAIM

I claim the ornamental design for a die cast key, as shown and described.

DESCRIPTION

FIG. 1 is a perspective view of the die cast key of the present invention.

FIG. 2 is a top plan view of the die cast key of FIG. 1.

FIG. 3 is a side view of the die cast key of FIG. 1.

FIG. 4 is a front view of the die cast key of FIG. 1. The

reverse side of the die cast key would be a mirror image.

FIG. 5 is the opposite side view of the die cast key of FIG. 3; and,

FIG. 6 is a bottom view of the die cast key of FIG. 1.

The phantom lines are for illustrative purposes only and do not form part of the design of the die cast key. The broken lines which illustrate the wording and functional part are not part of the design.
